FLIGHT SELECTOR INSTRUMENT FOR AIRCRAFT

Barnett Behrenfeld, Rego Park, and Gordon R. Anderson,
Levittown, N. Y., assignors to Sperry Rand Corpora-
tion, a corporation of Delaware

Application May 9, 1957, Serial No. 46,083

Term of patent 14 years

(Cl. D52—1)

Fig. 1

Fig. 2

Fig. 1 is a perspective view of a flight selector instrument for aircraft showing our new design.

Fig. 2 is a front elevational view thereof;

Fig. 3 is a side elevational view thereof;

Fig. 4 is a top plan view thereof; and

Fig. 5 is a bottom-plan view thereof.

Figs. 3, 4 and 5 are drawn to a somewhat smaller scale than Figs. 1 and 2. The lining on the drawing represents contrasting colored areas.

We claim:

The ornamental design for a flight selector instrument for aircraft, as shown and described.
